UNITED STATES PATENT OFFICE.

RUSSELL F. COLLINS, OF SPOKANE, WASHINGTON.

LIFE-PRESERVER.

1,129,958.

Specification of Letters Patent. Patented Mar. 2, 1915.

Application filed July 16, 1914. Serial No. 851,342.

To all whom it may concern:

Be it known that I, RUSSELL F. COLLINS, a citizen of the United States, residing at Spokane, in the county of Spokane and State of Washington, have invented a new and useful Life-Preserver; and I do hereby declare the following to be a full, clear, and exact description of the invention, such as will enable others skilled in the art to which is appertains to make and use the same.

This invention relates to a new and useful life preserver or buoy.

An object of the invention is to provide an improved life preserver constructed of heavy suitable waterproof material, not only to guard against the inflow of water, but to guard against puncturing.

A further object of the invention is the provision of a device of this nature having a plurality of air chambers adapted to be inflated, not only to maintain the life preserver afloat, but to guard against puncturing in such a manner as to prevent the escape of the entire inflation of air in the life preserver, which would cause the preserver and the person therein to sink.

Another object of the invention is the provision of a tapering life preserver, the air chambers being also tapering, and at the apex of the preserver a storage battery of sufficient voltage is arranged, which not only acts to supply current to a heating bulb, but also constitutes means of a ballast, not only to maintain the life preserver at a proper distance in the water, but to maintain the equilibrium thereof. In other words, to counterbalance the preserver.

Another feature of the invention is the provision of a foot board or rest spaced apart from the storage battery or ballast, thereby forming a heating compartment therebetween.

Another feature of the invention is the provision of a transverse web or strap, which the occupant straddles as a seat.

Another feature of the invention is the provision of an elastic shirred rubber yoke, designed to fit closely about the neck of the occupant, and also a hood fitting over the head of the occupant, said hood having proper openings for breathing, and sight openings properly windowed to protect the eyes from the water.

In practical fields the details of construction may necessitate alterations, falling within the scope of what is claimed.

The invention comprises further features and combination of parts, as hereinafter set forth, shown in the drawings and claimed.

In the drawings: Figure 1 is a view in elevation, partly in section of the improved life preserver or buoy constructed in accordance with the invention. Fig. 2 is a transverse sectional view on line 2—2 of Fig. 1, more clearly showing the plurality of inflated air chambers. Fig. 3 is an enlarged detail view in perspective of the lower apex end of the preserver. Fig. 4 is a horizontal sectional view on the line 4—4 of Fig. 2. Fig. 5 is a detail.

Referring more especially to the drawings, 1 designates an inner casing, and 2 an outer casing, whereas 3 and 4 denote intermediate casings. Between the several casings there are three air chambers 5, 6 and 7. The forward air chambers are inflated by means of the tube 8, which has branch tubes 9 entering the several chambers, there being the usual check valves as indicated at 10 to prevent the escape of air as the chambers are being filled. The rear air chambers are inflated by the tube 12 having branch tubes 13 and the usual check valves, similar to the first check valves. In using the life preserver these chambers are inflated, and if either the forward or rear outer wall or casing is punctured, which would cause a deflation of the chamber adjacent thereto, it will be seen that the remaining chambers will remain intact. It will be observed that these chambers are tapering toward the bottom or lower apex end of the preserver. The lower apex end of this preserver is provided with a suitable storage battery 14, which not only supplies current to the heating bulb or the like 15, but also constitutes a ballast for maintaining the equilibrium of the preserver or buoy. Spaced apart above the storage battery or ballast is a foot board or rest 16, suitably padded upon its upper surface as shown at 17, and upon the under surface the heater or bulb 15 is secured. The occupant of the preserver or buoy stands upon the foot rest or board, and straddles a heavy canvas web or leather strap or the like 18, which is secured at 19 detachably and adjustably to the inner face of the inner casing. The strap or web 18 is made detachable and adjustable, in order to be useful to different sized persons or occupants. A suitable belt or strap 20 is provided upon the inner portion of the inner

casing, so as to securely strap or fasten the occupant within the buoy or preserver. A suitable receptacle or the like 21 is also arranged upon the inner portion of the inner casing, in which a limited supply of water and food may be stored. Where the upper portions of the several casings merge together, as shown at 22 a suitable elastic rubber waterproofed yoke is connected in any suitable manner. This yoke 23 is not only elastic, but is designed to be shirred, so as to closely fit the neck of the occupant, as shown in the drawing. A suitable hood 24 is designed to fit over the head of the occupant and provided with water-tight connections as shown at 25, at the junction of the yoke and said casings. This hood is provided with suitable openings 26 to enable the occupant to breath, and additional openings 27 properly windowed to protect the eyes from the water. This life preserver or buoy may be made in various sizes, and strong and durable, so as to withstand rough usage.

25 The invention having been set forth, what is claimed as new and useful is:—

30 1. A life preserver comprising a plurality of casings having a plurality of inflated air chambers therebetween, said casings and the chambers gradually tapering to an apex at the lower portion of the preserver, a storage battery in the apex of the preserver for supplying current to an electric heater and constituting a ballast, a foot rest spaced apart above the storage battery, and a transverse web or strap connecting the opposite walls of the innermost casing constituting a seat for the occupant.

35 2. A life preserver comprising an inner-

most casing and an outermost casing and 40 intermediate casing having a plurality of inflated air chambers between said casing, said casings at the top of the life preserver merging together, an elastic shirred yoke connecting said casings where they merge 45 together, said casings and the chambers gradually tapering toward an apex at the lower end of the life preserver, heating means in the apex of the preserver, and a foot rest spaced apart above the heating 50 means.

3. A life preserver comprising an innermost casing and an outermost casing and intermediate casing having a plurality of inflated air chambers between said casing, 55 said casings at the top of the life preserver merging together, an elastic shirred yoke connecting said casings where they merge together, said casings and the chambers gradually tapering toward an apex 60 at the lower end of the life preserver, heating means in the apex of the preserver, and a foot rest spaced apart above the heating means, and a transverse web or strap 65 adjustably connecting the opposite walls of the inner casing constituting a seat for the occupant, and a hood on the upper portion of the life preserver having a water-tight joint at the junction of the merging of the casing.

70 In testimony whereof I have signed my name to this specification in the presence of two subscribing witnesses.

RUSSELL F. COLLINS.
